JAMES F. O'BRIEN, OF LOS ANGELES, CALIFORNIA.

CARTRIDGE-MAKING MACHINE.

1,129,809.

Specification of Letters Patent. Patented Feb. 23, 1915.

Application filed December 4, 1913. Serial No. 804,686.

To all whom it may concern:

Be it known that I, JAMES F. O'BRIEN, a citizen of the United States, residing at Los Angeles, in the county of Los Angeles, State 5 of California, have invented new and useful Improvements in Cartridge-Making Machines, of which the following is a specification.

This invention relates to a machine for 10 forming cartridges, for explosives or the like, from paper or similar material; and the invention consists in certain combinations and arrangements as are hereinafter specifically pointed out.

15 In its preferred form, this invention includes a rotatable hollow cylindrical mandrel capable of expansion and contraction, being preferably slit longitudinally and having a means for normally holding it expanded. Around this rotatable mandrel is 20 arranged an expansive frame carrying a number of rollers adapted each to press toward the mandrel and to press the paper sheet into engagement therewith. The 25 frame and rollers are open when the operation commences and, immediately the paper has been inserted, the rollers close down on the paper and the subsequent revolution of the mandrel causes the paper to roll about 30 the mandrel. The paper is fed to the mandrel with one end overhanging the mandrel end; and means are provided for folding the overhanging end of the paper over the end of the mandrel and over an ejector button 35 which normally rests in the end of the mandrel. When the rolling and folding operations have been completed, the ejector button is operated to remove the finished product from the mandrel.

40 The mechanism for accomplishing all of these operations are explained in detail in the following specification, the preferred form of the invention being shown in the accompanying drawings, in which,

45 Figure 1 is a side elevation of the improved machine, Fig. 2 is an elevation from the opposite side, Fig. 3 is an end elevation taken as indicated by line 3-3 of Fig. 1, Fig. 4 is an enlarged section taken as indicated by line 4-4 of Fig. 1, Fig. 5 is a plan of the portions shown in Fig. 4, Fig. 6 is an enlarged section showing the mandrel construction, and showing the position of a sheet of paper thereon. Figs. 7 and 8 show 50 the paper blank and the finished cartridge.

In the drawings the numeral 10 designates a suitable supporting frame for the mechanisms about to be described, 11 designates a drive shaft suitably journaled in the frame, and 12 a main shaft suitably journaled therein. The main shaft 12 carries a large gear 13 meshing with a pinion 14 on the drive shaft; and shaft 11 may be driven either by a hand crank 15 or by any suitable power. Directly mounted upon 55 said gear 13 is a gear ring 16 having spiral or diagonal teeth over a portion of its periphery and having a blank space 17 as best shown in Figs. 1 and 2. The teeth of gear ring 16 engage with a spiral gear 18 mounted upon hollow shaft 19 in suitable bearings 20 on the frame. This hollow shaft 19 carries the mandrel 21 upon which the cartridges are formed. The gear 13 carries a cam 25 adapted to operate a follower 26 mounted upon an arm 27 pivoted at 28. Arm 27 is connected by rod 29 with pivoted ejector arm 30 so that oscillations of arm 27 caused by the cam 25 will be transmitted to the ejector arm 30. The ejector arm 25 normally remains in the position shown in the drawing, a spring 31 normally holding the parts in the position shown. In Figs. 1 and 2 the mechanism is shown in such position that the ejector arm has just 60 been moved in the direction indicated by the arrow and has moved back to its normal position. The upper end of the ejector arm connects directly with an ejector rod 35 which extends through the hollow mandrel 21 to a point near its farther end. The 65 ejector rod 35 carries a cone 36 which normally engages coöperating members 37 on the inside of the mandrel to hold the mandrel normally expanded. The mandrel 70 is made in hollow cylindrical form and provided with any suitable number of longitudinal slits 38, which slits extend back from the end of the mandrel to a point where the mandrel enters the hollow shaft 19, (over 75 the whole operating portions of the mandrel) When the rod 35 is moved in the direction indicated, the cone 36 is removed from engagement with the members 37 and allows the mandrel to be contracted. On the 80 extreme end of the ejector rod 35 an ejector button 40 is loosely mounted. This ejector button is normally in the position shown in Fig. 6, or approximately in that position, filling the end of the mandrel and forming 85 a base against which the overhanging edges of the paper may be folded or crimped.

The button 40 has a concave outer face 41 and has a conical inner face 42 which enables it to be easily drawn into the mandrel. The button is mounted upon the rod 35, between a nut or other member 43 and the cone 36, so as to have a certain amount of independent motion. When the rod 35 is moved in the direction indicated, the cone 36 is moved out of the members 37 to allow the mandrel to slightly contract before the button 40 is moved at all. Movement of the button 40 causes removal of the finished cartridge from the mandrel; the rod 35 has sufficient movement to throw the finished cartridge clear of the mandrel.

There is a plurality of rollers 50 surrounding the mandrel, with axis parallel to the mandrel axis, and adapted to press a sheet of paper downwardly against the mandrel. These rollers 50 are mounted on expanding frames which are preferably constructed as follows: The rollers 50 are directly carried in bearings in links 51 arranged around the mandrel as best shown in Fig. 4 and arranged so that their inner edges 51^a are concentric with the mandrel and approach closely to its surface when the parts are in the positions shown in Fig. 4. The links and rollers are carried on suitable pivoted levers. There are preferably three sets of links and three sets of carrying levers, each set including a lever 55 pivoted on a suitable axle 56 and connected at its upper end at 57 directly with the uppermost link 51, so that the links and rollers are directly supported from the levers 55. The other levers 58 of each set extend under the mandrel and have ends 59 which engage notches 60 in the links 51^b, normally holding these links up in the position shown. A spring 61 holds the levers 55 and 58 toward each other, holding the parts normally in the position shown. The levers are spread apart and the rollers allowed to loosen around the mandrel by the following described mechanism. The levers 55 and 58 have extensions 55^a and 58^a carrying adjustable studs 62. These adjustable studs bear against a squared bar 63 mounted in suitable bearings 64 and adapted to be turned on its longitudinal axis by the operation of a cam 65 on a follower arm 66 which is directly attached to squared bar 63. Oscillation of the follower 66 and the bar 63 in the direction indicated in Fig. 3 will throw the levers 55 and 58 away from each other and loosen the rollers about the mandrel. During the period of loosening of the rollers, being the period of engagement of follower arm 66 by cam 65, a sheet of paper may be fed to the mandrel in the manner indicated at 69 in dotted lines in Fig. 4. This sheet of paper is fed against a guide stop formed by three guide fingers 70 each pivoted at 71 to one of the levers 55

and each having an extension 72 which engages an extension 73 on each of the levers 58. The ends 70^a of the guide fingers are adapted to fall to the surface of the mandrel when the levers 55 and 58 are spread apart; and the ends 70^a are all in a single line parallel to the axis of the mandrel, forming a stop guide parallel to the axis of the mandrel against which the forward end of the sheet may be pressed. The sheet is shown in Fig. 7. Its forward edge 75 is shoved under the uppermost roller 50 against the guide fingers 70, with one edge of the sheet overhanging the outer end of the mandrel. Immediately the sheet is fed into place the operation of the machine causes the rotation of the mandrel and causes the contraction of the rollers 50 about the mandrel to hold the sheet against it. The rollers rotate by frictional contact with the mandrel and the paper. The sheet rolls up about the mandrel and as is best illustrated in Fig. 6 with its end overhanging the ejector button 40. The rear edge 76 of the sheet is diagonal and the longer side edge 77 is the one for overhanging the end of the mandrel, it being at this end of the finished cartridge that the bottom is formed. The shorter side edge 78 winds about the mandrel and the diagonal edge 76 finally comes to the position somewhat as illustrated in Fig. 8. After the mandrel has made the required number of turns to wind the paper sheets completely about it, it is rotated one more complete revolution while the crimping of the overhanging portions of the sheet takes place. This crimping operation is caused by a crimping wheel 80 which has crimping teeth in its periphery as is best shown in Fig. 3. The crimping wheel is pivoted on an arm 81 which is itself pivotally mounted on a shaft 82. Normally the crimping wheel stands in the position shown in Fig. 3. A cam follower arm 83 is mounted upon the shaft 82 and adapted to be engaged by a cam 84 mounted upon the main shaft. This cam is so placed that immediately the paper has been entirely wound about the mandrel, the crimpler wheel 80 is oscillated toward the mandrel in the direction indicated by the arrow in Fig. 3. The crimpler wheel is free to revolve, and its teeth coming into contact with the paper overhanging the end of the mandrel cause that portion of paper tube to be crimped into corrugations and to be folded gradually inwardly to approximately the position illustrated in dotted lines in Fig. 6. The crimping wheel is held in this operative position during about one revolution of the mandrel, and is then allowed to return to its normal position under the influence of a spring 85. Immediately the crimpler wheel returns to its normal position, the crimp hammer 86 is op-

erated. This hammer is pivoted at 87 and has an arm 88 projecting as illustrated to be engaged by a plurality of pins 89 on the gear ring 16. These pins strike the arm 88 and cause the hammer 86 to strike the partially folded crimped paper at the end of the mandrel, pressing the paper down flat against the concave surface of the ejector button 40, finishing the end of the cartridge 10 in the form shown in Fig. 8. During this hammering operation, the mandrel is still revolving and stops revolution at just about the time the hammer makes its last impact. The blank space in the gear 16 then comes 15 opposite the gear 18 and the mandrel is stopped revolving while the ejector operates in the direction indicated to eject the finished cartridge, the button 40 pressing against the bottom of the finished cartridge. 20 During the back stroke of the ejector the mandrel is still at rest and a new sheet may be inserted as before described. After the new sheet is inserted the mechanism is in the position shown in the drawings and 25 ready to form the next cartridge.

I claim—

1. A cartridge making machine, comprising a rotatable hollow contractile mandrel, means for normally expanding the mandrel 30 including a longitudinally movable wedge operating within the mandrel, paper holding rollers arranged around the mandrel with axes parallel thereto, means to move the rollers to and from the mandrel to press 35 a paper sheet against the mandrel and to relieve said pressure, means for folding the end edge of the paper sheet across the end of the mandrel, and a longitudinally movable ejector within the mandrel, said ejector 40 and mandrel expanding wedge being coöperated so that the wedge is moved longitudinally to allow the mandrel to contract slightly before the ejector operates to remove a finished cartridge from the mandrel. 45 2. A cartridge making machine, comprising a rotatable hollow contractile mandrel, means for normally holding the mandrel expanded comprising a longitudinally movable cone within the mandrel and coöperating members on the inside of the mandrel, an ejector button normally within the end of the mandrel, an ejector rod loosely connected with the ejector button and rigidly connected with the expanding cone so that 50 longitudinal movement of the rod first causes movement of the cone and then causes movement of the ejector button, means for rolling a sheet of paper or the like around the mandrel with one edge over-hanging the mandrel end and the ejector button, means for folding the over-hanging edge of paper across the end of the mandrel and over the ejector button, and means for operating the ejector rod. 60 65 3. A cartridge making machine, comprising

ing a rotatable hollow contractile mandrel, means for normally holding the mandrel expanded comprising a longitudinally movable cone within the mandrel and members on the inside of the mandrel coöperating 70 with the cone, an ejector rod extending longitudinally through the mandrel and means for moving the rod longitudinally, said cone being rigidly mounted upon the rod, a conical ejector button loosely mounted on the 75 rod and normally closing the end of the mandrel, means for rolling a sheet of paper or the like around the mandrel with one edge overhanging the mandrel end and the button, said means including a mandrel rotating mechanism and an expansive roller carrying frame around the mandrel; rollers mounted on the frame with axes parallel to the mandrel axis, means to normally hold the roller frame contracted, and means to 80 expand the roller frame. 85

4. In a device of the character described, a rotatable mandrel, an expansible roller carrying frame surrounding the mandrel comprising a plurality of sets of links each 90 set encompassing the mandrel, levers arranged in pairs one pair for each link set, the levers of each pair being connected one to one end link and the other to the other end link, and means to move the levers to 95 and from each other.

5. In a device of the character described, a rotatable mandrel, an expansible roller carrying frame surrounding the mandrel comprising a plurality of sets of links each set 100 encompassing the mandrel, levers arranged in pairs one pair for each link set, the levers of each pair being connected one to one end link and the other to the other end link, a guide stop comprising a stop finger pivotally 105 mounted upon one lever of each set and engaging the other lever and having an end adapted to engage the mandrel surface when the levers are spread apart, and means to move the levers to and from each other. 110

6. A cartridge making machine or the like, comprising a hollow contractile mandrel, means for normally expanding the mandrel including a longitudinally movable wedge operating within the mandrel, means 115 for rolling a sheet about the mandrel to form a tube with its end overhanging the end of the mandrel, means for folding the end of the tube across the end of the mandrel, a longitudinally movable ejector within the mandrel, and a single operating means for both the ejector and the expanding wedge so that the wedge is moved longitudinally 120 to allow the mandrel to contract before the ejector operates to remove a finished cartridge from the mandrel. 125

7. A cartridge making machine or the like, comprising a hollow contractile mandrel, means for normally expanding the mandrel including a longitudinally movable 130

wedge operating within the mandrel, means for rolling a sheet about the mandrel to form a tube with its end overhanging the end of the mandrel, means for folding the 5 end of the tube across the end of the mandrel, a longitudinally movable ejector within the mandrel, an operating rod for the ejector and the wedge, the wedge being rigidly mounted upon said rod and the ejector 10 being loosely mounted upon said rod so that the rod and wedge may move a short distance before the ejector is moved.

8. A cartridge making machine or the like, comprising a hollow contractile mandrel, means for rolling a sheet about the mandrel to form a tube with its end overhanging the mandrel end, means for folding the end of the tube across the end of the mandrel to close the end of the tube, means for normally holding the mandrel expanded 20

including a longitudinally movable wedge operating within the mandrel, a longitudinally movable ejector button normally closing the end of the mandrel and adapted to be moved outwardly against 25 the closed end of the cartridge tube, and an operating rod for the wedge and ejector button, the wedge being rigidly mounted upon the rod and the ejector button loosely mounted thereon, so that the rod and wedge 30 may move a short distance to allow the mandrel to contract before the ejector button is moved against the end of the cartridge tube.

In witness that I claim the foregoing I have hereunto subscribed my name this 26th 35 day of November 1913.

JAMES F. O'BRIEN.
